UNITED STATES PATENT OFFICE

JAMES D. DYER, OF KANSAS CITY, MISSOURI

SCREEN HANGER MECHANISM

Application filed November 1, 1930. Serial No. 492,770.

My invention relates to improvements in screen hanger mechanisms.

It relates particularly to a hanger mechanism adapted for suspending a screen in the upper part of a window.

One of the objects of my invention is to provide a novel screen hanger mechanism which is simple, strong, durable, not likely to get out of order, which is readily applicable to the usual screen and window casing, which is cheap, which enables the screen to be easily and quickly hung in the window or removed therefrom, and to be disposed and releasably held in an open position, and which is efficient in operation.

The novel features of my invention are hereinafter fully described and claimed.

In the accompanying drawings, which illustrate my invention,

Fig. 1 is an outside elevation, partly broken away, of the preferred embodiment of my invention, shown applied to a screen which is mounted in a window.

Fig. 2 is an enlarged elevation of one of the screen hanger mechanisms, shown in Fig. 1, and shown mounted on the screen and casing, the screen being shown in the closed position.

Fig. 3 is a section on the line 3—3 of Fig. 2.

Fig. 4 is a section similar to Fig. 3, the screen, however, being shown swung outwardly from the closed position.

Fig. 5 is an enlarged section on the line 5—5 of Fig. 2.

Fig. 6 is a perspective, enlarged, of the hanger member shown in Figs. 1 to 5.

Fig. 7 is an outside elevation of a screen and window casing provided with two hanger mechanisms embodying a modification of my invention.

Fig. 8 is an enlarged elevation of one of the hanger mechanisms, shown in Fig. 7, mounted on a frame and casing partly broken away.

Fig. 9 is a section on the line 9—9 of Fig. 8, the screen being shown closed.

Fig. 10 is a view similar to Fig. 9, the screen being shown partly open.

Fig. 11 is an enlarged perspective view of the hanger member shown in Figs. 7 to 10.

Similar characters of reference designate similar parts in the different views.

Referring particularly to Figs. 1 to 6, 1 designates a hanger member comprising a flat plate fastened, as by screws 2, to the outer side and upper end of a screen frame 3 adjacent to one upper corner thereof. The two screws 2 are respectively mounted in the upper rail and adjacent stile of the screen frame, whereby the hanger member serves as a brace for binding the rail and stile together.

The hanger member 1 extends above the upper edge of the frame 3 and is adapted to lie against the outer side of the window casing 4 above the screen frame. That portion of the hanger member which projects above the screen frame 3 is provided with an opening comprising, preferably, a longitudinal slot 5 which converges upwardly in width.

The slot 5 is adapted to receive therethrough a supporting member having a threaded shank 6 inserted in the casing 4.

Said supporting member is provided at 75 the outer end of the shank 6 with a resilient compressible and expansible head 7, the upper end of which is convex and which extends upwardly and outwardly from the shank 6, and the lower end of which has in its under side a recess 8. The head 7 and shank 6 are preferably a resilient wire one end of which forms the shank 6 and the other end of which is part of the head 7 and is slideable vertically under the shank 6 on the casing 4.

For slidably anchoring the slideable portion 9 of the head 7 to the casing 4, a clip 10 fastened to the casing 4 embraces the vertical 90 slideable portion 9.

The head 7, when expanded, as shown in Fig. 3, is larger in diameter vertically than the length of the slot 5, so that the head 7 must be compressed in order to pass through the slot 5. This construction enables the head 7 to bear against the outer side of the hanger member 1 at the ends of the slot 5, thereby releasably holding the hanger member 1 from horizontal movement outwardly.

By swinging the lower end of the screen 100

frame 3 outwardly, the hanger member 1 will force upwardly the sliding portion 9 of the head 7, thus compressing the head, so as to permit the hanger member 1 to swing outwardly at its lower end to the position shown in solid lines in Fig. 4, in which position the hanger member 1 will be in the recess 8, permitting the head 7 to expand so as to hold the hanger member 1 and the screen frame 16 in the downwardly and outwardly inclined open position, shown in solid lines in Fig. 4.

The convex upwardly and outwardly extending upper part of the head 7, permits the hanger member 1 to be swung still further outwardly and upwardly to a position in which the head 7 will pass through the slot 5, and thus release the hanger member from the supporting member, when it is desired to remove the screen from the window. By reversing the operation and inserting the head 7 through the slot 5, the hanger member and screen frame may be replaced to the closed position, shown in Fig. 3.

It will be understood that two hanger members 1 will be respectively mounted on the upper corner portions of the frame 3, and that said hanger members will respectively engage two supporting members, mounted in the casing 4, as shown in Fig. 1, 30 and operative as has just been described.

In the modified form shown in Figs. 7 to 11, 11 designates a hanger member, similar to the hanger 1, similarly fastened by screws 2 to the top rail and adjacent stile of the 25 screen frame 3, and having a part extending above the screen frame provided with a longitudinal slot 12 and adapted to lie against the outer side of the casing 4, as shown in Fig. 9.

In the modified form, the supporting member 40 comprises a screw eye of usual type, having a threaded shank 13 adapted for insertion into the casing 4 above the frame 3, and having a circular head or eye 14 adapted to be inserted through the slot 12.

45 The screw eye is mounted in the casing 4 with the head bearing against the outer side of the casing. When the screen is inserted in the window, the head 14 is inserted through the slot 12, the hanger member 11 resting at the upper end of the slot 12 on the convex 50 upwardly and outwardly extending upper edge of the head 14, which thus supports the hanger member 11 and frame 3 and holds the hanger member from horizontal outward movement, but permitting the lower end of the hanger member 11 to be swung outwardly, to open the screen, or to permit the removal 55 of the screen and hanger member, by swinging the hanger member 11 upwardly and moving it outwardly, together with the screen frame 3.

60 In both forms of my invention, the heads or eyes 7 and 14 by reason of their convex upwardly and outwardly extending upper edges support the screen hanger members and hold

them from horizontal outward movement from the closed position, but permit them to be swung outwardly and upwardly to an open position or for removal from the window.

I do not limit my invention to the structures shown and described, as other modifications, within the scope of the appended claims, may be made without departing from the spirit of my invention.

What I claim is:—

1. In a screen hanger mechanism, a hanger member adapted to be fastened to a screen frame and having an opening, and a supporting member having a portion adapted to be fastened to the top rail of a window casing, 70 said supporting member having a resilient head adapted for insertion through said opening, and when so inserted being compressed between the upper and lower ends of said opening, said head extending upwardly and outwardly from said portion and at its upper edge being adapted to engage the outer side of said hanger member, whereby the latter is held from horizontal outward movement, but is permitted to swing at its lower end 75 outwardly, the lower side of said head having a recess adapted to receive said hanger member at the lower end of said opening, said recess being spaced from the inner end of said head, whereby, when said hanger member is in said recess, said resilient head will expand and hold said hanger member in an 80 open position.

2. In a screen hanger mechanism, a hanger member adapted to be fastened to a screen frame and having an opening, and a resilient supporting wire having a shank at one end 85 adapted to be inserted into the top rail of a window casing, the other end of said wire being adapted to be moved upwardly toward 90 said shank, said wire extending upwardly and outwardly from said shank and adapted to hold said hanger member from horizontal outward movement but permitting it to swing at its lower end outwardly, said wire being 95 adapted for insertion through said opening and adapted to engage said hanger member at the upper and lower ends of said opening, when said hanger is in the closed position of the screen, and in said position releasably 100 holding said hanger member from swinging at its lower end outwardly and being compressible to permit said hanger member 105 swinging at its lower end outwardly when outward pressure is applied to the hanger member.

3. In a screen hanger mechanism, a hanger member having a longitudinal slot and adapted to be fastened to a screen frame with said slot disposed above the upper edge of said frame, and a supporting member comprising a resilient wire adapted for insertion at one end into the top rail of a window casing and formed into a partly closed expansible and compressible eye adapted for insertion, when 115 120 125 130

compressed through said slot, the upper edge of said eye extending upwardly and outwardly from said rail, when the supporting member is mounted thereon, the lower part of 5 said eye being formed into an external recess adapted to receive said supporting member, the latter, when in said recess being releasably held in a downwardly and outwardly inclined position, the lower portion of said eye 10 being compressed and moved upwardly when said hanger member is swung into and from the closed position.

4. In a screen hanger mechanism, the combination with a window casing and a screen frame mounted therein, of a hanger member fastened to said frame and extending above the upper edge thereof and having in the portion above said frame a longitudinal slot, and a supporting member having a shank 20 mounted on said casing above said frame and provided with a compressible and expansible resilient eye adapted to be compressed when forced through said slot through which the eye is insertible, said lower portion of said eye having in its under side a recess adapted 25 to receive said hanger member which, in said recess, is releasably held by said eye in a downwardly and outwardly inclined position, and guiding means mounted on said casing 30 in which a movable part of said eye is vertically slidable.

5. In a screen hanger mechanism, the combination with a window casing and a screen frame mounted therein, of a hanger member 35 fastened to and extending above the upper edge of said frame and in that portion which is above said frame having a longitudinal slot, and a supporting member comprising a wire having a shank portion mounted in 40 said casing above said frame and having its other end bearing against said casing and intermediate of said other end and said shank having an eye which is insertible through said slot, the upper edge of said eye being convex 45 and extending upwardly and outwardly from said shank and adapted to support said hanger member and to hold it from outward horizontal movement, the outer side of said eye having a recess spaced from said casing and 50 adapted to receive said hanger member, said eye, when said hanger member is in said recess, holding said hanger member in an open position.

In testimony whereof I have signed my 55 name to this specification.

JAMES D. DYER.
